STRAIGHT BAR KNITTING MACHINE

Patrick Gideon McCarthy, Loughborough, and Denis Winfield, Shepshed, England, assignors to William Cotton Limited, Baxter Gate, Loughborough, England

Application May 23, 1955, Serial No. 510,213

Claims priority, application Great Britain
January 28, 1953

4 Claims. (Cl. 66—130)

This application is a continuation-in-part of our patent application Serial No. 350,851, filed April 24, 1953, entitled "Straight-Bar Knitting Machines."

This invention is for improvements in or relating to Cotton's patent or other straight bar knitting machines and has particular although not exclusive reference to those multi-head machines known as pant frames or underwear and outerwear machines which are the subject of our patent application No. 350,851 from which the present application is a continuation-in-part. In these latter machines knitted garments other than knitted footwear may be produced, and adjustable lead screws and associated mechanism are provided such that work which may be termed "non-symmetrical" may be produced. In such a machine there has also been provided a flexible drive carrier control mechanism (e. g. as disclosed in our patent application No. 350,852) for positively driving thread carriers, and anti-rebound mechanism for carriers.

The present invention is generally concerned with these machines which have that type of flexible drive carrier control mechanism in which there is employed a flexible element such as a chain for transmitting drive to the thread carriers, also wherein traverse of the carriers may be limited by sprocket wheels on which the element rides changing the path of the element to effect and release a releasable connection between the carriers and the flexible element, and further wherein the sprocket wheels are mounted on sprocket boxes which are adjustable on lead screws to vary the traverse of the carriers. Primarily the invention is concerned with the provision, in these latter machines, of anti-rebound mechanism for the thread carriers. In said flexible drive carrier control mechanism wherein said releasable connection consists of a roller device on the chain which is adapted by the changing path of the chain to ride into and out of a slot in a slotted slide block connected to thread carriers, it is known to provide anti-rebound mechanism for the carriers comprising, for each sprocket box, a catch abutment on the slide block which is adapted to be engaged, automatically at the end of the traverse of the carriers, with a spring pressed anti-rebound stop comprising a bolt which is mounted on the sprocket box and is releasable by automatic means. In operation, the bolt is automatically connected to the catch abutment immediately the carriers reach the end of the movement i. e. some time before the chain reaches the end of its movement, and the automatic means disengages the bolt from the catch at the commencement of the chain, i. e. some time prior to the return of the carriers; a disadvantage of this is that there is thus undesirable freedom of movement of the carriers during the early return movement of the chain.

An object of the invention is to avoid this undesirable freedom of movement of the carriers.

The invention provides, in a Cotton's patent or other straight bar knitting machine having flexible drive control mechanism of the type referred to, anti-rebound mechanism for the thread carriers comprising two pairs of

2

spring pressed stops for respectively connecting the sprocket boxes to a part carrying the thread carriers, whereof one, anti-rebound, stop of each pair is controlled by cam means in addition to its spring and the other is controlled only by its spring. The second stop is of self-acting type to automatically connect said part and the appropriate sprocket box at the end of the carrier traverse, and to automatically release when the carrier starts its reverse, the stop in the meantime maintaining the connection throughout the period during which the chain completes its stroke after the carrier traverse (whereupon the cam means acts to retract the anti-rebound stop, which is of one-way-locking type to prevent rebound of said part and the carrier) and returns a distance before the carrier starts to reverse. Preferably the cam means is constituted by a cam for each anti-rebound stop on a shaft rotatable at half the speed of the main cam shaft. The two pairs of stops are conveniently bolts mounted respectively on the sprocket boxes, and said part conveniently has abutments complementary to the bolts to co-operate with them.

The said cam means preferably includes a shaft rotatable from the draw cross shaft at half the speed of the main cam shaft, and a cam thereon for each anti-rebound stop in such a manner that each anti-rebound stop can be maintained in retracted inoperative position throughout any required predetermined period in appropriate alternate courses thereby to allow for the production of what may be termed "non-symmetrical" work for which it may be necessary for a carrier to start and stop its traverse at one side of the centre of a needle bar, and also maintained in projecting operative position throughout any required predetermined period in the remaining courses such that, as desired, they are always projecting when the sprocket boxes are adjusted for fashioning.

The mechanism as above may be provided in combination and co-operation with anti-rebound stops acting directly on the carrier bars and which are operable from the half speed shaft.

40 The invention further provides in a Cotton's patent or other straight bar knitting machine having a thread carrier driving chain, roller means on the chain adapted to be coupled to and uncoupled from a slotted slide block, carrying thread carriers, by traversing the chain round sprocket wheels mounted on a pair of spaced sprocket boxes which are adjustable towards and away from each other on lead screws and cause change of direction of the chain at each box to carry the roller into and out of the slot in the slide block at the variably spaced locations of the boxes, anti-rebound mechanism for the thread carriers comprising two pairs of spring pressed bolts on the sprocket boxes respectively for respectively engaging with and disengaging from the slide block at the end of the carrier traverse to connect the slide block to and release it from the sprocket boxes, whereof one, anti-rebound, bolt of each pair is of one-way-locking type and is controlled by cam means from a half speed shaft in addition to its spring means, and the other is of self-acting type, being controlled only by its spring to connect with and release from the slide block automatically upon movement of the slide block to engage with and disengage from it and to maintain the connection throughout an intermediate period whilst the slide block stationary and the chain continues to traverse to the end of its movement and back to re-engage with the slide block.

45 The above and other features of the invention set out in the appended claims are incorporated in the construction which will now be described, as a specific embodiment with reference to the accompanying drawings 50 in which:

Figure 1 is a diagrammatic plan view of a machine

for employing anti-rebound mechanism according to the invention.

Figure 2 is a cross sectional view through the upper part of the machine. Figure 2A is a cross sectional view through the lower part of the machine in continuation of Figure 2.

Figure 3 is a diagrammatic illustration of the operation of the anti-rebound mechanism.

Figure 4 is a detail face view of part of the anti-rebound mechanism, and

Figure 5 is a detail cross sectional view of part of said mechanism.

Referring now to Figure 1, the straight bar machine illustrated incorporates two main selvedge stops 1, 2 with associated mechanisms and two auxiliary stops 3, 4 and associated mechanisms, a main carrier control or drive mechanism 5, an auxiliary carrier control or drive mechanism 6, thread carrier rods 7, 8 and 9, a driving shaft 10 driving a cam shaft 11, and a half speed shaft 12 (Figures 2, 3 and 5) driven through the medium (not shown) of a chain for example from the draw cross shaft. The main stops 1, 2 are shown (in Figure 1) for the carrier rod 7 and are adjustable on lead screws 14, 15 respectively simultaneously with the adjustment of sprocket boxes 16, 17 for the carrier control or drive mechanism 5 and for this purpose lead screws 18, 19 of said mechanism 5 may be respectively connected to the lead screws 14, 15 by suitable means indicated by way of example at 20 and 21. The two screws 14, 15 overlap two auxiliary screws 22, 23 on which the auxiliary stops 3 and 4 are mounted, and the carrier rod 8 is shown associated with these stops 3 and 4 and with the sprocket boxes of the carrier control or drive mechanism 6 similar to the arrangement for the carrier 7.

Thread carrier bar 7 is connected to the carrier control 5 and carrier rod 8 is connected to the carrier control 6.

Referring now to Figure 2, this shows suitable mounting details for the screws 14, 15, 22 and 23, screws 14 and 15 being supported by brackets 24, 25 respectively from the top back rail 26 and disposed with the screw 14 above the screw 15. The boxes 1 and 2 are conveniently guided on a steady shaft 27 and they include anti-rebound bolts indicated at 28 which may be rendered operative and inoperative on any of the carrier bars 7, 8 and 9 through the medium of link and lever mechanism indicated generally at 29 from a cam 30, on said half speed shaft 12 and driving arm 32 with a truck 33.

The auxiliary screws 22, 23 may be carried by a bracket 34 from the head rail 35 and the stop boxes 3, 4, thereon may be guided on a shaft 36 and may include anti-rebound bolts 37 which may be rendered operative and inoperative on the carrier bar 8 by link and lever mechanism indicated generally at 38 through the medium of said truck arm 32 and truck 33 from the cam 30 on said half speed shaft 12.

Referring now to Figure 3 this diagrammatically illustrates the operation of the anti-rebound stop mechanism and Figures 4 and 5 show parts of said mechanism in detail. More specifically there is a carrier driving chain 39 traversing over sprockets 40-43, and 44-46, and the slide block 47 carrying a thread carrier 7 and having a slot 48 formed by vertical members 49, 50 between which a roller 51 on the chain 39 is normally disposed. The sprockets 40, 41 are mounted on the sprocket box 16 and the sprockets 42, 43 are mounted on the sprocket box 17. The slide block 47 has fixed on it a catch abutment 52 which is locatable by adjustable screw 53 (Figure 4) and a female abutment 54 having a V-shaped notch 55. For co-operating with the catch abutment 52 there is a spring pressed bolt 56 of one-way-locking type carried by the sprocket box 16 and adapted to be retracted by a lug 57 thereon engaging a vertically displaceable bar 58 which is vertically displaceable through the medium of a rod 59, bell crank device 60 and truck 61

engageable with a cam 62 on the aforesaid half speed shaft 12. For co-operation with the female abutment 54 there is a spring pressed bolt 63 carried by said sprocket box 16 and of self-acting type having a V-shaped lower nose 64 for automatic releasable engagement with and disengagement from the V-shaped notch 55 on the female abutment 54. Thus when the slide block 47 is moved to the left in Figures 3 and 4 the catch abutment 52 and the female abutment 54 automatically engage with the anti-rebound bolt 56 and the bolt 63 respectively (the anti-rebound bolt 56 dropping in behind the abutment 52) precisely at the time the roller 51 carried by the chain 39 changes direction by travelling vertically between the two sprockets 40 and 41 and thus disengages the roller 51 from the slot 48 in the slide block 47 and ceases to impart further driving force to the slide block 47; the abutments 52 and 54 thereby hold the slide block 47 and associated thread carrier steady at the end of its traverse and remains thus until the end of the traverse of the chain 39. Immediately the chain 39 begins to reverse, the anti-rebound bolt 56 is automatically raised by the cam 62 clear of the catch abutment 52 and thus is immediately released from the slide block 47 ready for the latter to return. However the slide block 47 does not generally return immediately because the roller 51 on the chain 39 has in the meantime traversed to a position beyond the sprocket box 16; instead, the roller 51 must first travel back until it again becomes disposed between the two sprockets 40 and 41 and re-engages in the slot 48 of the slide block 47, before the slide block 47 is returned. On these occasions it will be understood that the other bolt 64 and the female abutment 52 remain connected and this ensures that the slide block 47 is maintained steady throughout this period after the anti-rebound bolt 56 has been released and until the roller 51 re-engages the slot 48 in the slide block 47. The cam 62 has a suitable rise and fall such that, by virtue of it being on the half-speed shaft 12, the anti-rebound bolt 56 will remain in retracted position throughout desired predetermined periods in appropriate alternate courses to allow for the production of the aforesaid non-symmetrical work in which the carrier may start and stop at one side of the centre of the needle bar. The operation of the anti-rebound bolt 56 from the half speed shaft 12 is also such that, as desired, it always remains in projected operation during adjustment of boxes 16, 17 for fashioning. Similar anti-rebound stop mechanism to that just described is provided for operation during traverse of the slide block 47 to the right in Figures 3 and 4, and relevant parts are indicated by reference numerals 52' to 62'. The anti-rebound bolt 56' of the latter mechanism operates in opposite directions to the former anti-rebound bolt 56.

What we claim is:

1. A straight bar knitting machine comprising in combination, a thread carrier, means for driving of the thread carrier comprising a horizontally slidable slide member carrying the thread carrier, a reciprocatable flexible element, a releasable driving connection between the slide member and the reciprocatable element, control means comprising a pair of control members at spaced locations in the travel of the reciprocatable element to make and break the releasable driving connection at said spaced locations so that travel of the thread carrier in opposite directions by the reciprocating element is commenced and terminated by control of the spaced control members and the reciprocatable element completes a constant amplitude of travel after each thread carrier travel, a pair of horizontal adjustable lead screws one above and a second below the horizontal path of the slide member, a screw nut on each of said spaced control members one mounting its control member on the upper lead screw for adjustable positioning of the control member horizontally above said path of the slide member and the other mounting its control member on the lower lead

screw for adjustable positioning of this control member horizontally below said path of the slide member, whereby the amplitude of travel of the thread carrier is variable, anti-rebound stop means comprising a spring biased bolt on each spaced control member one for cooperating with a fixed stop on top of the slide member and the other for cooperating with a fixed stop on the underside of the slide member, cam operated means for operating on each anti-rebound bolt, a guide bar for each bolt to enable operation of each bolt by the cam operated means at any position of adjustment of the spaced control members, and auxiliary stop means comprising a spring biased bolt on each spaced control member one for cooperating with a fixed stop on top of the slide member and the other for cooperating with a fixed stop on the underside of the slide member.

2. A straight bar knitting machine comprising, in combination, a thread carrier, means including a reciprocatable flexible driving element having a constant amplitude of travel for driving the thread carrier control means comprising spaced control members effecting releasable connection between the thread carrier and the flexible driving element at variably spaced locations in the element's travel so that the element travels part way with the thread carrier and part way without it, and means operating to hold the thread carrier stationary at the ends of its travel comprising self-operating anti-rebound stop means consisting of a spring biased anti-rebound bolt slidably mounted in each control member and a fixed stop for each anti-rebound bolt on the slide member, a main cam shaft, a half speed shaft driven at half the speed of the main cam shaft, and cam operating means to release the bolts consisting of a cam for each bolt on the half speed shaft and link and lever mechanism operable by each cam to withdraw one bolt against its spring pressure when the flexible driving element completes its travel after each thread carrier travel, and self operating and releasing stop means comprising a spring biased bolt slidably mounted in each control member and having a V-shaped end and a fixed stop, for each of these spring biased bolts, which is on the slide member and has a V-shaped notch to receive said V-shaped bolt end.

3. A straight bar knitting machine comprising, in combination, a thread carrier means for driving of the thread carrier comprising a horizontally slidable slide member carrying the thread carrier, a reciprocatable flexible element, a releasable driving connection between the slide member and the reciprocatable element, control means comprising a pair of control members at spaced locations in the travel of the reciprocatable element to make and break the releasable driving connection at said spaced locations so that travel of the thread carrier in opposite directions by the reciprocating element is commenced and terminated by control of the spaced control mem-

bers and the reciprocatable element completes a constant amplitude of travel after each thread carrier travel, a pair of horizontal adjustable lead screws parallel to and spaced from each other and the horizontal path of the slide member, a screw nut on each of said spaced control members one mounting its control member on one of the lead screws and the other mounting its control member on the other lead screw for adjustable positioning of the control members horizontally along said path of the slide member, whereby the amplitude of travel of the thread carrier is variable, anti-rebound stop means comprising a spring biased bolt on each spaced control member one for cooperating with one fixed stop on the slide member and the other for cooperating with a second fixed stop on the slide member, cam operated means for operating on each anti-rebound bolt, a guide bar for each bolt to enable operation of each bolt by the cam operated means at any position of adjustment of the spaced control members, and auxiliary stop means comprising a spring biased bolt on each spaced control member one for cooperating with a third fixed stop on the slide member and the other for cooperating with a fourth fixed stop on the slide member.

4. A straight bar knitting machine comprising, in combination, a thread carrier means including a reciprocatable flexible driving element having a constant amplitude of travel for driving the thread carrier, control means comprising spaced control members effecting releasable connection between the thread carriers and the flexible driving element at variably spaced locations in the element's travel so that the element travels part way with the thread carrier and part way without it, and means operating to hold the thread carrier stationary at the ends of its travel comprising self-operating anti-rebound stop means consisting of a spring biased anti-rebound bolt slidably mounted in each control member and a fixed stop for each anti-rebound bolt on the slide member, cam operated means to release the anti-rebound bolt and link and lever mechanism operable by each cam to withdraw one anti-rebound bolt against its spring pressure when the flexible driving element completes its travel after each thread carrier travel, and self-operating and releasing auxiliary stop means comprising a spring biased bolt slidably mounted in each control member and having a V-shaped end and a fixed stop, for each of these spring biased bolts, which is on the slide member and has a V-shaped notch to receive said V-shaped bolt end.
